UNITED STATES PATENT OFFICE.

JAMES S. ALEXANDER, OF JACKSONVILLE, FLORIDA.

WEIGHING-SCOOP.

SPECIFICATION forming part of Letters Patent No. 734,653, dated July 28, 1903.

Application filed November 22, 1902. Serial No. 132,479. (No model.)

To all whom it may concern:

Be it known that I, JAMES S. ALEXANDER, a citizen of the United States, residing at Jacksonville, in the county of Duval and State 5 of Florida, have invented a new and useful Weighing-Scoop, of which the following is a specification.

The object of this invention is to provide a novel weighing-scoop having mechanism 10 that will indicate the weight of material placed therein, the arrangement being such that there will be no strain upon the weighing mechanism when the scoop is forced into the material during the filling operation, said 15 mechanism being brought into play upon lifting the scoop.

Another object is to provide an instrument of this character having very little friction and therefore correspondingly great accuracy. 20 The preferred embodiment of the invention is illustrated in the accompanying drawings and is described in the following specification. An inspection of the claims hereto appended will show, however, that the construction illustrated and described is open to 25 various changes and modifications.

In the drawings, Figure 1 is a side elevation of the improved scoop. Fig. 2 is a vertical sectional view through a portion of the same. 30 Fig. 3 is a horizontal sectional view taken on the line $x-x$ of Fig. 2. Fig. 4 is a detail perspective view of the connecting-frame, and Fig. 5 is a sectional view through a portion of the same. Fig. 6 is a detail view of a simple form of gravity-resisting means that may 35 be employed in connection with a scoop.

Similar reference-numerals indicate corresponding parts in all the figures of the drawings.

40 In the embodiment shown a handle member 10 and a scoop member 11 are employed, which are arranged longitudinally of each other and are constructed as follows: The member 10 is provided with the usual handle 45 12, carrying at its inner end an enlarged casing 13, within which is fitted a boxing secured to said casing by suitable screws or other fastening devices 14. This boxing consists of spaced transversely-disposed walls 15 and 16, 50 connected at their edges by end walls 17, into which the fastening devices 14 are screwed. The walls 15 and 16 are provided intermedi-

ate their edges with upright slots 18 and 19, which are preferably in alinement. Arranged in the upper portion of the casing 13, which 55 is contracted for the purpose, is a suitable balance, which may be of any desirable construction and is provided with an exposed pointer 20, coacting with a circular scale 21.

The bowl member is of substantially the 60 usual shape, comprising a semicylindrical wall 22, the outer edge of which is rounded, the inner end of said member having a backing-wall 23, that preferably extends above the wall 22. To this rear wall 23 is attached a connecting-frame consisting of an upright supporting-bar 24, having feet 25 at its upper and lower ends, which are fastened to the wall 23. This supporting-bar is arranged in the boxing 65 of the handle member, the feet projecting 70 through a slot 18. Secured to the supporting-bar are cross-arms 26, which extend into the boxing that constitutes a guideway therefor, these cross-arms carrying at their ends anti-friction-rollers 27, the upper of said rollers 75 bearing against the inner face of the outer wall and the lower rollers in like manner bearing against the opposing face of the inner wall. As a result the connecting-frame has a slidable interlocking engagement in 80 the guideway and secures the two members of the instrument together. Journaled upon the feet 25 are other antifriction-rollers 28, which are located in the slot 18 and are arranged to bear against the edges of the same, 85 said edges being provided with outstanding flanges 29, that also serve to stiffen the wall 15. Still other rollers 30 may be journaled upon the rear wall 23 of the bowl member, 90 being arranged to rest against the outer face of the transverse wall 15. Projecting from the rear face of the supporting-bar 24 is a stud 31, which extends through the slot 19 of the rear wall 16, and to this stud is fastened a link 32, which is connected to the balance 95 in a manner readily understood. An anti-friction-sleeve, as 33, may be revolvably mounted upon the stud and engage in the slot 19, as shown in Figs. 2 and 3. The balance may be of any well-known form desired, 100 a spring gravity-resisting device being illustrated in Fig. 6.

In this structure it will be understood that the various antifriction-rollers will have suf-

ficient space to freely revolve, or, in other words, should they come into contact with one wall they will be out of contact with the other, though this play must necessarily be 5 extremely limited to prevent looseness of the parts. When the scoop is filled by forcing it into the material, it will be evident that the rear thrust will be brought against the walls 15 and 16 and no strain will be imparted to the balance. As soon, however, as the scoop is lifted the weight in the bowl member will cause the same to move downwardly with relation to the handle member and the indicator will be actuated, thus showing the 15 amount of material in the scoop. It will be evident that this structure is very simple, and as the friction is reduced to a minimum, because of the various rollers used, great accuracy can be obtained.

20 From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages of the invention.

25 Having thus described my invention, what I claim as new, and desire to secure by Letters Patent, is—

30 1. In an instrument of the class described, the combination with a bowl member in the form of a scoop having an open front end and a rear wall, of a handle member located in rear of the bowl member, an upright guideway arranged on one member transversely of the instrument, connecting means rigidly secured to the other member and having a movable interlocking engagement therewith, said members being thereby relatively movable transversely of the instrument, and a scale carried by one member having a connection 35 with the other.

35 2. In an instrument of the class described, the combination with a bowl member having its front upright end open, of a handle member arranged longitudinally of the bowl member and having an upright guideway in its inner end, a connecting-frame secured to the rear end of the bowl member and having a movable interlocking engagement in the guideway, said members being thus relatively 40 movable transversely of the instrument, and a scale mounted upon the handle member and attached to the connecting-frame.

45 3. In an instrument of the class described, the combination with a handle member having an upright transversely-disposed wall, of a movable bowl member having its upright front end open, and a frame carried by the bowl member and slidably associated with the transverse wall, being movable transversely of the instrument, said frame bearing 50 against the wall.

4. In an instrument of the class described, the combination with a handle member having a transversely-disposed wall provided with a slot, of a movable bowl member, and a frame carried by the bowl member and projecting through the slot, said frame having oppositely-extending outstanding portions that engage the inner face of the wall on opposite sides of the slot. 75

5. In an instrument of the class described, the combination with a handle member having a transversely-disposed wall provided with a slot, of a movable bowl member, and a frame carried by the bowl member and projecting through the slot, said frame having outstanding arms provided with rollers that bear against the inner face of the wall. 80

6. In an instrument of the class described, the combination with a handle member having a transversely-disposed wall provided with a slot, of a movable bowl member, and a frame carried by the bowl member and comprising an upright supporting-bar that projects through the slot, and spaced cross-arms 90 carried by the bar and extending across the inner face of the wall. 85

7. In an instrument of the class described, the combination with a handle member having a transversely-disposed wall provided with a slot, of a movable bowl member, and a frame carried by the bowl member and comprising an upright supporting-bar having feet that project through the slot, spaced cross-arms carried by the bar and extending 100 across the inner face of the wall, rollers journaled upon the cross-arms and bearing against the walls, and rollers journaled upon the feet and arranged in the slot. 95

8. In an instrument of the class described, the combination with a handle member having spaced transverse walls forming a guideway therebetween, of a bowl member, and a frame attached to the bowl member and extending between the transverse walls, said frame having rollers that bear against the opposing inner faces of the walls. 105

9. In an instrument of the class described, the combination with a handle member having spaced transverse walls forming a guideway therebetween, said walls having upright slots, of a bowl member, a frame attached to the bowl member and extending through one of the walls and fitting between the transverse walls, said frame having rollers that 115 bear against the opposing inner faces of the walls, a stud projecting from the frame through the slot of the inner wall, and a scale 120 having a connection with the stud. 120

In testimony that I claim the foregoing as my own I have hereto affixed my signature in the presence of two witnesses.

JAMES S. ALEXANDER.
